UNITED STATES PATENT OFFICE.

GEORGE MILLER MARSHALL, OF GROSSE ISLE, MANITOBA, CANADA.

BUILDING CONSTRUCTION.

1,127,058.

Specification of Letters Patent.

Patented Feb. 2, 1915.

Application filed January 4, 1913. Serial No. 749,172.

To all whom it may concern:

Be it known that I, GEORGE MILLER MARSHALL, of the village of Grosse Isle, in the Province of Manitoba, Canada, have invented certain new and useful Improvements in Building Construction, of which the following is the specification.

My invention relates to an improvement in building construction and the object of the invention is to primarily provide a new form of block for building purposes especially designed for a hollow wall construction and further to provide a means for reinforcing the wall so constructed and for attaching the wall to the usual steel framework of the building.

With the above object in view the invention consists essentially in the arrangement and construction of parts hereinafter more particularly described and later pointed out in the appended claims.

Figure 1 is a side view of one of my blocks. Fig. 2 is a plan view of a section of a wall formed in accordance with my invention. Fig. 3 is a longitudinal sectional view through the wall, the section being taken in the plane denoted by the line X—X' Fig. 2. Fig. 4 is a vertical sectional view through the walls, the section being taken in the plane denoted by the line Y—Y' Fig. 3. Fig. 5 is an end view of one of the blocks. Fig. 6 is a plan view of a further portion of the wall showing a modified form of reinforcing bar. Figs. 7 and 8 are views of the assembled wall with my device in use.

In the drawings like characters of reference indicate corresponding parts in each figure.

1 represents a cement or other similar composition block more or less rectangular in form and provided at the top with a V-shaped groove 2 and at the bottom with a V-shaped groove 3 and at one end with a V-shaped groove 4 and at the opposite end with an extending V-shaped tongue 5. The corners of the block are notched away on the inner side as indicated at 6, 7, 8 and 9, those on the outer side of the block being retained as shown at 10, 11, 12 and 13. Centrally and on the inner side edge of the block I have formed V-shaped notches 14 and 15 which notches open into the grooves 2 and 3. The above details complete the construction of the block. I will now describe how it is used in building hollow walls.

Two companion parallel structures or walls 16 and 17 are erected side by side, each wall being formed from a number of my blocks built in with mortar in much the same manner as brick is now laid. The companion walls are built at the same time and as soon as the first layer is laid, it being understood that the tongues and grooves at the ends of adjoining blocks are fitted one into the other. Binding strips 18 of a diamond shaped cross section are laid in cement in the grooves 2 and a second layer of the blocks is placed on each of the companion walls, it being desirable to stagger or alternate the joints formed at the ends of the blocks in each layer. This operation is continued to whatever height it is desired to build the hollow wall and as the building operation proceeds it is necessary for strengthening purposes to tie the companion walls together. This is accomplished by laying in or inserting at proper intervals reinforcing bars 19. These bars are more or less in the form of an I-beam in cross section which permits the heads 19' and 19² of the bars to rest snugly within the grooves 2 and 3 of adjoining blocks. By staggering or alternating the joints between the ends of the blocks in different layers it will be seen that the notches 14 and 15 of one block form with the notched away corners of adjoining blocks in a different layer a diamond shaped opening best shown in Fig. 3 of the drawing. These openings permit the bars 19 to be laid in the wall as the bodies of the bars pass in the completed structure through the diamond shaped openings, the ends 19' and 19² being received in the grooves 2 and 3 as already described. It is of course understood that bars 18 will be omitted from the portions of the grooves 2 and 3 which receive the ends 19' and 19² of the bars 19.

By exercising a little care, a builder would have no difficulty in placing these bars 19 in the wall as the notches and cut out corners will so to speak register with little difficulty if the various layers are laid carefully and properly. The outer faces of the companion walls will present a smooth surface as the corners of the block are not cut away, neither do notches appear in them on this side. I might mention, that if at any time, through improper laying it is found impossible to fit in a reinforcing bar where desired, this can be readily accomplished by the mason knocking off the required corners

of the block and chipping out the notch with his trowel.

The bars as above described are mounted for the most part in the wall. At points 5 where it is desired to connect the wall with an adjoining steel structure forming in reality the frame-work of a building I have supplied a modified form of bar much the same as the one just described with the addition of an extending finger or arm 20 (see 10 Fig. 6), the finger being also diamond shaped in cross section.

In Fig. 6, 21 represents a portion of a vertically disposed I-beam forming part of 15 the steel structure of a building. In order to connect my wall with the steel structure I insert in the wall and adjoining the I-beam a number of reinforcing bars of the second form instead of those 19. They are placed 20 so that the arms or fingers 20 appear on opposite sides of the I-beam passing around the flange and butting in against the web. Preferably the bars 20 are staggered, that is not more than one bar being placed in the 25 same groove.

This construction anchors the wall to the beam and consequently to the erected steel structure. Where these latter bars are placed in the wall the mason will have to notch 30 away sufficient of the blocks to allow the arms to protrude through the inner face of the wall. In other words, the notch located in the center of the the block will have to be continued completely across the block while 35 the adjoining corners of the blocks in the next layer, adjoining the notch, will have to be knocked entirely off, thereby forming a

diamond shaped opening on the outer side of the block similar to that previously referred to on the inside of the block.

What I claim as my invention is:

1. The combination with companion walls composed of spaced apart blocks having notches in the inner side edges thereof and being provided with grooves in their top and bottom edges, of a vertically disposed beam, bars connecting and reinforcing the companion walls, said bars having heads fitting in said grooves, the end of said bars adapted to enter said notches, and certain of said bars having fingers passing beyond the inner face of the wall and receiving the beam aforesaid.

2. The combination with companion walls composed of spaced apart blocks having notches in the inner side edges and grooves in the top and bottom edges thereof, of a vertically disposed beam, binding strips in portions of the grooves between the top and bottom edges, bars connecting and reinforcing the companion walls, and located in staggered relation one to the other in the walls, certain of said bars having oppositely disposed fingers passing beyond the inner face of the wall and receiving the beam aforesaid, and portions of said last mentioned bars being adapted to enter the notches in the inner side edges of said blocks.

Signed at Winnipeg this 29th day of October 1912.

GEORGE MILLER MARSHALL.
